DESIGN FOR A LAMP HOLDER

Herman Powell, Chicago, Ill.

Application February 18, 1948, Serial No. 144,583

Term of patent 3½ years

(Cl. D48—20)

To all whom it may concern:

Be it known that I, Herman Powell, a citizen of the United States of America, residing at Chicago, in the county of Cook and State of Illinois, have invented a new, original, and ornamental Design for Lamp Holder, of which the following is a specification, reference being had to the accompanying drawing, forming part thereof.

Fig. 2 is a side elevational view thereof.

Fig. 3 is a plan view thereof.

Fig. 4 is a fragmentary bottom view thereof.

I claim:

The ornamental design for a lamp holder, as shown.

HERMAN POWELL.
